CLAIM

The ornamental design for a protective package, as shown and described.

DESCRIPTION

FIG. 1 is a top perspective view of the protective package of the present invention;

FIG. 2 is a bottom plan view thereof;

FIG. 3 is a front elevational view thereof; and,
 FIG. 4 is a right side elevational view thereof; the left side elevational view being a mirror image thereof.

The rear elevational view is the same as FIG. 4.
